No Drawing. Application March 3, 1937, Serial
No. 128,824. In Germany October 11, 1935

9 Claims. (Cl. 95—88)

Our present invention relates to photographic desensitizing.

One of its objects is a photographic desensitizing bath. Another object is a desensitizing process for light-sensitive photographic materials. Another object are the desensitizers. Further objects will be seen from the detailed specification following hereafter.

This invention is a continuation in part of our application Ser. No. 104,442 filed Oct. 7, 1936. That application relates to a process for desensitizing light-sensitive silver halide emulsions by use of the unsubstituted and alkylated taurides of anthraquinone-carboxylic acids and/or sulfonic acids.

This invention is based on the observation that there are also useful as desensitizers instead of the aforesaid substances other acid amides of the anthraquinone series in which at least 1 hydrogen atom of the amide-group is replaced by a residue containing a sulfonic or carboxylic acid group. When only 1 hydrogen atom of the amide-group is thus replaced the other hydrogen atom may also be replaced by any other organic residue, for example an alkyl or aryl residue. For example the amino group may be substituted as follows:

Substances suitable for use in the invention are, for instance, the sarcosides of the anthra-

quinone-carboxylic acids and anthraquinone-sulfonic acids, for example the compounds of the formulae:—

and

The compounds may be used in a preliminary bath or as an addition to the developer. Where they are used in a preliminary bath the desensitizing effect may be considerably enhanced by addition of sodium sulfite.

The following examples illustrate the invention:

(1) 1 gram of the sodium salt of anthraquinone-2-sulfosarcoside and 25 grams of anhydrous sodium sulfite are dissolved in 1 litre of water. The photographic layers are bathed for 2 minutes in this solution, after which they may be developed in the bright-green light.

(2) 0.75 gram of the sodium salt of anthraquinone-2-carboxylsarcoside and 25 grams of anhydrous sodium sulfite are dissolved in 1 litre of water. The photographic layers are bathed for 2 minutes in this solution, after which they may be developed in the bright-green light.

(3) Ortho-chromatic and panchromatic photographic layers are developed in 1 litre of a developer of the following composition:

40

1 litre of water,
8 grams of 1-hydroxy-4-methylaminobenzene-sulfate,
125 grams of anhydrous sodium sulfite,
5.8 grams of anhydrous sodium carbonate,
2.5 grams of potassium bromide,
0.4 gram of the sodium salt of anthraquinone-2-sulfophenylglycide.

(4) Ortho-chromatic and panchromatic photo-

graphic layers are developed in one litre of a developer of the following composition:

- 5 1 litre of water,
8 grams of 1-hydroxy-4-methylaminobenzene-
sulfate,
125 grams of anhydrous sodium sulfite,
5.8 grams of anhydrous sodium carbonate,
2.5 grams of potassium bromide,
10 0.75 gram of the sodium salt of anthraquinone-2-
sulfophenyltauride.

What we claim is:

1. A process of desensitizing a light-sensitive silver halide emulsion which comprises treating said silver halide emulsion with a compound selected from the group consisting of N-aryltaurides and amides of one of the group consisting of anthraquinone carboxylic acids and anthraquinone sulfonic acids, said amides being selected from the group consisting of amides the nitrogen of which is linked to a radical selected from aliphatic and aryl radicals containing a carboxyl group, amides the nitrogen of which is directly attached to an aryl radical and linked to a radical selected from aliphatic and aryl radicals containing a carboxyl group, and amides the nitrogen of which is directly attached to an alkyl radical and linked to a radical selected from aliphatic and aryl radicals containing a carboxyl group.

2. A process of desensitizing a light-sensitive silver halide emulsion which comprises treating said silver halide emulsion with a compound selected from the group consisting of N-aryltaurides and amides of one of the group consisting of anthraquinone carboxylic acids and anthraquinone sulfonic acids, said amides being selected from the group consisting of amides the nitrogen of which is linked to a radical selected from aliphatic and aryl radicals containing a carboxyl group, amides the nitrogen of which is directly attached to an aryl radical and linked to a radical selected from aliphatic and aryl radicals containing a carboxyl group, and amides the nitrogen of which is directly attached to an alkyl radical and linked to a radical selected from aliphatic and aryl radicals containing a carboxyl group, and with an alkali sulfite.

3. A process of desensitizing a light-sensitive silver halide emulsion which comprises immersing said silver halide emulsion before development in a preliminary bath containing a compound selected from the group consisting of N-aryltaurides and amides of one of the group consisting of anthraquinone carboxylic acids and anthraquinone sulfonic acids, said amides being selected from the group consisting of amides the nitrogen of which is linked to a radical selected from aliphatic and aryl radicals containing a carboxyl group, amides the nitrogen of which is directly attached to an aryl radical and linked to a radical selected from aliphatic and aryl radicals containing a carboxyl group, and amides the nitrogen of which is directly attached to an alkyl radical and linked to a radical selected from aliphatic and aryl radicals containing a carboxyl group.

4. A process of desensitizing a light-sensitive silver halide emulsion, which comprises immersing said silver halide emulsion before development in a preliminary bath containing a compound selected from the group consisting of N-aryltaurides and amides of one of the group consisting of anthraquinone carboxylic acids and anthraquinone sulfonic acids, said amides being

selected from the group consisting of amides the nitrogen of which is linked to a radical selected from aliphatic and aryl radicals containing a carboxyl group, amides the nitrogen of which is directly attached to an aryl radical and linked to a radical selected from aliphatic and aryl radicals containing a carboxyl group and amides the nitrogen of which is directly attached to an alkyl radical and linked to a radical selected from aliphatic and aryl radicals containing a carboxyl group, and an alkali sulfite. 5 10

5. A process of desensitizing a light-sensitive silver halide emulsion, which comprises developing said silver halide emulsion in a bath containing developing agents and a compound selected from the group consisting of N-aryltaurides and amides of one of the group consisting of anthraquinone carboxylic acids and anthraquinone sulfonic acids, said amides being selected from the group consisting of amides the nitrogen of which is linked to a radical selected from aliphatic and aryl radicals containing a carboxyl group, amides the nitrogen of which is directly attached to an aryl radical and linked to a radical selected from aliphatic and aryl radicals containing a carboxyl group, and amides the nitrogen of which is directly attached to an alkyl radical and linked to a radical selected from aliphatic and aryl radicals containing a carboxyl group.

6. A process of desensitizing a light-sensitive silver halide emulsion, which comprises developing said silver halide emulsion in a bath containing developing agents, a compound selected from the group consisting of N-aryltaurides and amides of one of the group consisting of anthraquinone carboxylic acids and anthraquinone sulfonic acids, said amides being selected from the group consisting of amides the nitrogen of which is linked to a radical selected from aliphatic and aryl radicals containing a carboxyl group, amides the nitrogen of which is directly attached to an aryl radical and linked to a radical selected from aliphatic and aryl radicals containing a carboxyl group, and amides the nitrogen of which is directly attached to an alkyl radical and linked to a radical selected from aliphatic and aryl radicals containing a carboxyl group, and an alkali sulfite.

7. A bath for desensitizing a light-sensitive silver halide emulsion comprising a compound selected from the group consisting of N-aryltaurides and amides of one of the group consisting of anthraquinone carboxylic acids and anthraquinone sulfonic acids, said amides being selected from the group consisting of amides the nitrogen of which is linked to a radical selected from aliphatic and aryl radicals containing a carboxyl group, amides the nitrogen of which is directly attached to an aryl radical and linked to a radical selected from aliphatic and aryl radicals containing a carboxyl group, and amides the nitrogen of which is directly attached to an alkyl radical and linked to a radical selected from aliphatic and aryl radicals containing a carboxyl group, and an alkali sulfite.

8. A developer for developing light-sensitive silver halide emulsion layers comprising developing agents and as a desensitizer a compound selected from the group consisting of N-aryltaurides and amides of one of the group consisting of anthraquinone carboxylic acids and anthraquinone sulfonic acids, said amides being selected from the group consisting of amides the nitrogen of which is linked to a radical selected from aliphatic and aryl radicals containing a carboxyl group, amides 70

the nitrogen of which is directly attached to an aryl radical and linked to a radical selected from aliphatic and aryl radicals containing a carboxyl group, and amides the nitrogen of which is directly attached to an alkyl radical and linked to a radical selected from aliphatic and aryl radicals containing a carboxyl group.

9. A developer for developing light-sensitive silver halide emulsion layers comprising developing agents, as a desensitizer a compound selected from the group consisting of N-aryltaurides and amides of one of the group consisting of anthraquinone carboxylic acids and anthraquinone sulfonic acids, said amides being selected from the

group consisting of amides the nitrogen of which is linked to a radical selected from aliphatic and aryl radicals containing a carboxyl group, amides the nitrogen of which is directly attached to an aryl radical and linked to a radical selected from aliphatic and aryl radicals containing a carboxyl group, and amides the nitrogen of which is directly attached to an alkyl radical and linked to a radical selected from aliphatic and aryl radicals containing a carboxyl group, and an alkali sulfite. 5
